UNITED STATES PATENT OFFICE.

WILLIAM L. COOP, OF DETROIT, MICHIGAN, ASSIGNOR TO CONTINUOUS TRAIN CONTROL CORPORATION, OF DETROIT, MICHIGAN, A CORPORATION OF MICHIGAN.

BRAKE-CONTROLLING VALVE MECHANISM.

Application filed November 25, 1925. Serial No. 71,335.

This invention relates to train control systems whereby electro-magnetic waves are propagated in the rails of each block into which the track is divided and include means whereby the wave lengths are determined by the occupancy of the track ahead, which systems further comprise loop collector coil circuits on the locomotive for picking up such electro-magnetic waves and utilizing them for the purpose of permitting or obstructing the flow of current through electron tubes on the locomotives and of relays controlled by such currents to govern the operation of electro-pneumatic valves connected to the air brake systems of the locomotives.

This invention consists of an automatic brake controlling valve mechanism connected to the train line pipe and normally controlled by an electro-pneumatic valve and a forestalling key, and electrical circuits between said key and the electro-pneumatic valve whereby the latter may receive electrical energy to prevent the operation of the brake-controlling valve mechanism; said automatic valve mechanism being constructed to release the train pipe air pressure to a predetermined degree unless the forestalling key is actuated within a predetermined time, such air pressure release occurring notwithstanding the addition of air to the train line pipe during such release.

It further consists of the details of construction illustrated in the accompanying drawing and particularly pointed out in the claims.

The air brake mechanism constituting the present invention is designed to be used in connection with instrumentalities on the locomotive which are controlled by electro-magnetic waves flowing in the track rails over which the locomotive is passing, and attention is called to the Thomas E. Clark Patent No. 1,262,637, dated April 16, 1918, which shows propagating mechanism for electro-magnetic waves attached to the exit ends of the blocks into which the track is divided. Each installation is controlled by the next installation ahead and functions to propagate current of one wave length, say 8000 meters, when the conditions of the block of track pertaining to such installation are for safety or "clear", and current of another wave length, say 6000 meters, when the conditions of such block are for "danger". Any

other desired means may be employed to propagate such currents under "clear" and "danger" conditions.

The track installations adapted to the present train control devices are of such power and wave lengths that only a limited length of track at the exit end of each block is energized by these installations sufficiently to affect the instrumentalities on the locomotive. These instrumentalities are not affected while passing over the remainders of the blocks.

The locomotive instrumentalities embody two collector coils 100 and 101, one for each wave length, mounted on the locomotive where they can be influenced by the lines of force of such electro-magnetic waves. These connect to two electron tubes 102 and 103 which have the usual characteristic that when negative potential accumulates in the grids, the flow of electrons from the filaments to the plates is interrupted and therefore substantially stops the flow of current in the plate circuits. These plate circuits embody relays normally energized by the flow of the current in the plate circuits.

I prefer to use a two-voltage generator 104 which may be driven in any desired manner. The common wire to this generator for both voltages is the heavy wire 105. When the coil 101 cuts lines of force of a current in the rails of say 16,000 meters wave length, electro-magnetic current flows from this coil over wire 106 to the grid of tube 103, the grid leak 107 connecting this wire with the return wire 109, the usual condenser 108 being connected into this circuit, which may be tuned to the desired wave length by the adjustable condenser 110. The heating circuit for the filament of this tube is from the generator 104 over the wire 112, resistance 113, which reduces the voltage from say 32 to 12 volts, wires 114, 115 and 116, filament of tube 102, wires 117, 109 and 118, filament of tube 103, wire 119, adjustable resistance 120 to common wire 105.

The reason for passing this current over the wires 115, 116, 109 and 118 is to cut out the current to both filaments should either of the coils 100 and 101 be broken through accident. But otherwise, current flows to these filaments at all times that the generator is in operation.

The receiver circuit of the coil 100 comprises the wires 122 and 123, adjustable

condenser 124 and wires 125, 114 and 115. The grid condenser 126 and grid leak 127 serve to impose negative potential on the grid of tube 102. When the grid of tube 103 has sufficient negative potential to obstruct the flow of the plate circuit, insufficient current flows to the relay 128 over the common wire 105, adjustable resistance 120, wire 119, filament to plate in tube 103, and wire 132 to this relay, from which current would normally flow over wire 130, armature 128^b and wire 129 to the high voltage side of the generator.

But as this circuit is interrupted because of lack of sufficient current to energize this relay, its armature *a* completes the following circuits for the red lamp R: from the common wire 105, wire 131, armature 128^a, wire 133, relay 134 and wires 135 and 114 to the generator. This now energized relay 134 attracts its armatures and the circuit from common wire 105, armature 134^b, wire 136, lamp R and wires 138 and 112 is established, a resistance 139 being provided to protect 25 the low voltage lamps.

Therefore, when the coil 101 picks up current, the red lamp R burns in the cab.

Should the coil 100 pick up current, then the tube 102 would pass insufficient plate 30 current and the relay 140 would be de-energized, and a circuit consisting of the common wire 105, wire 142, armature 140^a, wire 143, green lamp G, and wires 138 and 112 would be completed. The green lamp G 35 therefore burns during only the interval that the locomotive is passing over the section of track in which the "clear" current is found. The red light, however, when it starts burning, keeps on burning until the coil 100 40 picks up "clear" current from an energized section at the exit end of a next block, and this results from the circuit of its relay 134 being closed through the armature 140^a, wire 144, armature 134^a, wire 133, relay 134, wires 45 135, 114 and 112. But when the relay 140 becomes de-energized by reason of the coil 100 picking up current, this circuit to relay 134 is opened and the red lamp ceases to burn. No current will pass to this red lamp until 50 the coil 101 again picks up current.

An electro-pneumatic valve is employed to control the operation of the air brakes and consists of a body 9 having a series of superimposed chambers. A magnet 160 is mounted in the upper chamber and has lead wires 161 and 162, and this magnet, when energized, draws down the armature 163 and the stem 164, which carries the valve 165 which normally closes the passage between the chamber 166 to which the pipe 167 connects, and the chamber 168 which has a relief passage 169. The second valve 170, on this stem, normally opens the passage between the chamber 166 and the chamber 171 to 55 which the pipe 172 connects.

The pipe 172 connects to the main air reservoir and the air pressure within the chamber 171 together with the small spring 173 are sufficient to hold the valve 170 onto its seat, unless the magnet is energized to hold down this valve and the stem. The pipe 167 connects to the brake control mechanism which is held in normal position, as will be described later on, by the pressure of air from the main reservoir, through pipe 172 and 167. But when the magnet is de-energized, the valve 170 closes the passage between these pipes and the control air escapes through the relief passage 169.

So long as relay 128 is energized, current flows to the magnet of this valve 9 over common wire 105, wire 131, armature 128^a, wire 145, forestalling key 146, and wire 162, and from the valve 9 over wires 161 and 112 to the generator. But when the coil 101 picks up current and the relay 128 is de-energized, this circuit is opened and the connection between pipes 167 and 172 is closed, which will result in the setting of the air brakes unless forestalled by the depression of the key 146, which temporarily closes a circuit from the relay 128 over wires 130 and 147, depressed key 146, wire 148, a pressure controlled switch 36—37 to be explained later on, and wires 149 and 129. This switch 36—37 is normally closed and the depression of the key 146 will therefore cause the relay 128 to be re-energized, in which position its circuit will be maintained as heretofore described until the coil 101 again picks up "danger" current.

In the ordinary air brake system installed on many of the locomotives in use in this country, two manually operated brake control valves 1 and 4 and an air operated distributing valve 3 are employed. The valve 1 connects to the pipe 2 which in turn connects to the train pipe 15 and its function is to release the air in this pipe 2, which results in the application of the train brakes, to admit air to this pipe from the main pressure tank which results in the release of the train brakes and to control the action of the distributing valve 3 whose function is to apply and release the locomotive brakes simultaneously and proportionately to the action of the train brakes.

The independent valve 4 functions to admit air from the main pressure tank to the locomotive air pipe (not shown), which results in the application of the locomotive brakes, independently of the train brakes, and to release the pressure on this air pipe releases the locomotive brakes independently of the train brakes, which may be desirable when a heavy train is on a down grade and the engineer wishes to save his locomotive brakes while still using his train brakes.

The distinction between the valves 1 and 4 is primarily that when valve 1 releases

the pressure on the train pipe, the brakes are applied, but when valve 4 releases the pressure on its air pipe, the brakes are released. On the other hand, an increase of pressure on the train pipe releases the train brakes but pressure applies the locomotive brakes. As the two valves are interconnected, it is evident that leakage of train pipe pressure at the valve 3 to the valve 4 may cause application of the locomotive brakes. In order to prevent this, a manually operated cock was provided to permit escape of any such pressure in the locomotive air pipe to the valve 1 and the open air, and this cock was closed when two locomotives operated together as a "double-header", in which case the brakes of one locomotive had to be under the control of the engineer of the other. This leakage during "double-heading" would be watched and released by the second engineer.

When the valve 1 was in brake-release or running position and the cock was open, this leakage escaped through that valve, but when this valve was in brake-applying or "lap" position, the escape was prevented so that the locomotive brakes would be applied by the action of the distributor valve 3. Theoretically, such leakage should not occur, but in actual practice it is sufficient to require the cock above mentioned.

In the present system, I have substituted an air operated valve 7 for the cock above mentioned for the reason that an application of the brakes because of the operation of the automatic train control system shown in the drawing may occur when the valve 1 is in running position, in which event no application of the locomotive brakes would result unless the by-pass provided for this leakage is closed. The open stop cock would therefore prevent the application of the locomotive brakes. The air operated valve 7 therefore is open during normal operation of the locomotive but closed during the operation of the automatic train control system. The construction and operation of the distributor valve 3 and its relation to the above described mechanism is fully set forth in U. S. Patent No. 1,664,836 granted Apr. 3, 1928, to C. B. Stone and need not be repeated.

As above explained, when the coil 101 picks up "danger" current, the magnet 160 becomes de-energized and the pipe 167 is connected to the relief vent 169. The spring 13 will therefore press the valve 12 against its seat 14. As soon, however, as the magnet 160 is re-energized, air under pressure will flow from the pipe 172 past the valve 170 through pipe 167 to the space above the piston 10 and open the passage between the pipe 6 and the automatic valve 3.

The brake-control mechanism shown in

cross section at the middle of the drawing embodies a valve chamber 20 with a slide valve 21 therein connected to a stem 22 which is slideable by a piston 23 in the small cylinder 24. Below this chamber 20 is a second cylinder 25 containing a piston 26 connected to a stem 27 carrying the valve 28 which normally engages a seat 29 forming part of the chamber 30. Below the chamber 30 is another cylinder 32 in which the piston 33 is slideable, being normally held up by the spring 34 on the stem 35, and this stem carries an arched electrical contact 36 normally engaging the contact blocks 37 and 37^a. The wires 148 and 149 connect to the contacts 37 and 37^a respectively. The cap 38 protects this switch.

The drawing shows the piston 23 and valve 21 just after the pressure in the outer end of the cylinder 24 has been reduced because of the magnet 160 being deenergized, the valve 170 closing the passage between the pipes 167 and 172 and the small valve 165 opening the passage from the pipe 167 to the vent 169. This movement of the valve 21 is caused by air flowing from train pipe 15 through passages 40 and 41 and acting on a second piston 42 on the stem 22.

While the valve 21 was in its normal position against the shoulder 31, air under train pipe pressure flowed from the chamber 20 through the port 43 in the valve 21, through the passage 44 to the upper end of the cylinder 25, through the passages 45 and 46 and pipe 47 to the lower chamber 48 of the valve body 49. From this chamber, air flows through pipe 50 to the tank 51.

At the same time the small valve 53 was held off its seat in the small chamber 54 at the end of the main valve chamber 20 by the valve 21, the stem of the valve 53 being loose in its support and permitting a slow flow of air from this chamber 20 to the control tank 55 through pipe 56 and into the upper chamber 57 of the valve 49.

A smaller flexible diaphragm 59 and a larger flexible diaphragm 60 are mounted in the valve body 49 and support the valve 62 which normally opens the vent to the pipe 63 which connects to a passage 64 opening into the space 67 below the valve 21.

When the valve has reached the position shown, the spring 66 forces the small valve 53 onto its seat, preventing leakage from the tank 55 which retains normal train pipe pressure. The valve 21 by means of its port 67 connects the passage 64 and pipe 63 to the whistle 68, and air flows from above the piston 26 and from the tank 51 through the pipe 63 to this whistle. The reduction of air pressure above the piston 26 is rendered slow by this tank 51. When the downward air pressure on the piston 26 and stem 27 falls to less than the upward air pressure thereon, the piston and valve

will rise and air from the train pipe will rush down into the chamber 32, depressing the piston 33 and escaping through the holes 70. At the same time the contacts 36 and 37 separate, opening the forestalling-key circuit.

So long, therefore, as the pressure above the piston 26 is at not less than a certain ratio to the train pipe pressure, the circuit 10 between the forestalling key and the valve 9 may be closed and the engineer may prevent the application of the brakes thereby, the circuit to the electro-pneumatic valve 9 being established as above described.

15 But if the engineer delays depressing his forestalling key until the air pressure above the piston 26 is sufficiently reduced to permit the air pressure below it to raise it and the valve 28, the rush of air downward opens 20 the switch between the wires 148 and 149 and holds this switch open until the air pressure on the train line is sufficiently reduced to cause an application of the air brakes, and also until the valve 1 is brought 25 to "lap" or "brake application" position. Should the engineer feed air into the train pipe in an endeavor to release the brakes, such added air would assist in holding the 30 valve 28 open, but if he assists in reducing this train pipe pressure, the valve 28 will close earlier.

The upper diaphragm 59 of valve 49 is always under initial train pipe air pressure. When the pressure above the piston 26 and 35 below the diaphragm 60 has fallen so that the total pressure below the diaphragm 60 is less than the total pressure above the diaphragm 59, the valve 62 closes and prevents further reduction, which results in 40 the piston 26 forcing the valve 28 to its seat, provided, of course, the valve 1 is at "lap" position. The piston 33 is then lifted by its spring 34 and the contacts 36 and 37 engage 45 to close the forestalling-key circuit, so that the engineer can reset the relay 128 as before described.

The details of construction of this brake-controlling valve mechanism, the proportions of its parts and the pipe connections may all 50 be changed by those skilled in the art without departing from the spirit of my invention as set forth in the following claims.

I claim—

1. In an air brake system for railway 55 trains embodying an electrically controlled valve adapted to be energized upon the depression of a forestalling key to prevent the application of the brakes and circuits therefore, the combination of an automatic valve 60 body connected to the train line pipe and embodying a valve operable by the train pipe pressure to release the pressure within said pipe, said valve being normally held closed while the electrically controlled valve is 65 energized, and means operable by the air

escaping from the train pipe to open the circuit between said key and electrically operated valve.

2. In an air brake system for railway trains embodying an electrically controlled valve adapted to be energized upon the depression of a forestalling key, the combination of an automatic valve body embodying a cylinder and a piston therein and a valve connected to said piston, said cylinder connecting to the train pipe of the brake system, the pressure within the cylinder on both sides of the piston being normally that within the train pipe, means to release the pressure above the piston upon the de-energization of said electrically controlled valve to permit the piston and the valve attached thereto to release the train pipe pressure, and a switch operating mechanism adapted to be actuated by the air escaping from the train pipe to open the circuit to said forestalling key.

3. In an air brake system embodying an electro-pneumatic valve adapted to be energized upon the depression of a forestalling key and a circuit between the key and valve, an automatic valve connected to the train pipe and normally controlled by the electro-pneumatic valve to permit the escape of train pipe pressure when the electro-pneumatic valve is de-energized, and means operable by the escaping air when the train pipe pressure has fallen a predetermined amount to open the circuit between the key and electro-pneumatic valve to prevent it from obstructing the automatic application of the brakes.

4. In an air brake system for railway trains embodying an electro-pneumatic valve to cause or prevent the automatic application 105 of the brakes according to electric currents picked up from the rails, a forestalling key and a circuit adapted to be closed thereby whereby the valve may be energized to prevent such application, an automatic valve 110 embodying a pressure chamber, a tank connected thereto containing air under normal train pipe pressure, means controlled by said electro-pneumatic valve to relieve the pressure in said tank and chamber, a train pipe 115 connected to said automatic valve, means in said automatic valve to permit the discharge of the pressure in said train pipe when the pressure in the tank has decreased a predetermined degree, and means operated by the 120 air escaping from the train pipe to open the said circuit between said key and electro-pneumatic valve to render the electro-pneumatic valve inoperative to prevent application of the brakes.

5. In an air brake system for railway trains embodying an electro-pneumatic valve to cause or prevent the automatic application 125 of the brakes according to electric currents in the rails, an automatic valve body embodying 130

- a cylinder, a piston therein and passages in said valve body to carry train pipe pressure on the inner side of said piston, a train pipe connected to the cylinder on the outer side of 5 said piston, a valve connected to said piston and adapted to open a passage for the release of pressure from the train pipe, means controlled by the electro-pneumatic valve to release the pressure on the inner side of the 10 piston or to prevent such release to permit or prevent the opening of such valve, and means operated by the air escaping from the train pipe to render said electro-pneumatic valve inoperative until the brakes are applied.
- 15 6. In an air brake system for railway trains embodying an electro-pneumatic valve to cause or prevent the automatic application of the brakes according to electric currents in the rails, an automatic valve body embodying 20 a cylinder, a piston therein and passages in said valve body to carry train pipe pressure on the inner side of said piston, a train pipe connected to the cylinder on the outer side of said piston, a valve connected to said piston and adapted to open a passage for the release of pressure from the train pipe, means controlled by the electro-pneumatic valve to release the pressure on the inner side of the piston or to prevent such release to 25 permit or prevent the opening of such valve, and means operated by the air escaping from the train pipe to render said electro-pneumatic valve inoperative until the brakes are applied, said means embodying an electric 30 switch and energizing circuits to said valve which are opened by said switch.
7. In an air brake system for railway trains embodying an electro-pneumatic valve to cause or prevent the automatic application 40 of the brakes according to electric currents in the rails, an automatic valve body embodying a cylinder, a piston therein and passages in said valve body to carry train pipe pressure on the inner side of said piston, a train pipe connected to the cylinder on the outer side of said piston, a valve connected to said piston and adapted to open a passage for the release of pressure from the train pipe, a slide valve and passages 45 controlled thereby to release the pressure on the inner side of the piston or to prevent such release to permit or prevent the opening of such valve, and means operated by the air escaping from the train pipe to render 50 said electro-pneumatic valve inoperative until the brakes are applied.
- 55 8. In an air brake system for railway trains embodying an electro-pneumatic valve to cause or prevent the automatic application 60 of the brakes according to electric currents in the rails, an automatic valve body embodying a cylinder, a piston therein and passages in said valve body to carry train pipe pressure on the inner side of said piston, a train pipe connected to the cylinder on the outer side of said piston, a valve connected to said piston and adapted to open a passage for the release of pressure from the train pipe, means controlled by the electro-pneumatic valve to release the pressure on the inner side of the piston or to prevent such release to permit or prevent the opening of such valve, and means operated by the air escaping from the train pipe to render said electro-pneumatic valve inoperative until the brakes are applied.
- 65 9. An air brake system for controlling railway trains embodying an electro-pneumatic valve adapted to be energized to prevent the reduction of train pipe pressure which causes application of the brakes, an 70 automatic valve body to which the train pipe is connected, a pressure chamber and movable means therein to normally prevent the escape of the air in the train pipe, a valve to permit the escape of the pressure in said 75 chamber to cause the escape of train pipe pressure, a valve body and a pair of diaphragms therein of different sizes, and a valve connected thereto to cause stopping of such escape of train pipe pressure when such 80 pressure has dropped a predetermined degree by preventing further escape of pressure from said pressure chamber.
- 85 10. In an air brake system for railway trains, an electrically controlled valve adapted to be energized to prevent the application of the brakes, an electric circuit 90 for said valve, an automatic valve body connected to the train pipe and embodying a valve operable by train pipe pressure to release the pressure within said train pipe, said valve being normally held closed while the electrically controlled valve is energized, and means operable by the air escaping from the train pipe to open said circuit to the 95 electrically controlled valve.
11. In an air brake system for railway trains embodying a train pipe for compressed air which acts as the medium to prevent application of the brakes, an automatic 100 valve body connected to the train pipe and embodying a valve operable by train pipe pressure to release the pressure within said train pipe, electrically energized means to cause the valve to retain said pressure, and an electrical circuit therefor, and means operated by the air escaping from the train pipe when said valve is opened to open said 105 electrical circuit.
- 120
